ICE CREAM CARTON

Harry I. Roccaforte, Chicago, and Elverse M. Jordan, Wilmette, Ill., and William C. Inch, Whittier, Calif., assignors to Weyerhaeuser Company, Tacoma, Wash., a corporation of Washington

Filed Mar. 10, 1967, Ser. No. 6,164

Term of patent 14 years

(Cl. D9—240)

Fig. 1.

Fig. 2.

FIGURE 1 is a front perspective view of an ice cream carton, showing our new design; and

FIGURE 2 is a front elevational view thereof.

The side opposite that shown in FIGURE 1 is substantially a mirror image of the side shown, while the rear and bottom walls are substantially plain.

The essential feature of the design resides in the particular configuration of the front cover panel which is scored as shown.

We claim:

The ornamental design for an ice cream carton, as shown and described.
